UNITED STATES PATENT OFFICE.

WENSEL MORAVA, OF CHICAGO, ILLINOIS.

GAS OR OIL MOTOR FOR BICYCLES.

SPECIFICATION forming part of Letters Patent No. 608,968, dated August 9, 1898.

Application filed March 22, 1897, Serial No. 623,573. (No model.)

To all whom it may concern:

Be it known that I, WENSEL MORAVA, a citizen of the United States, residing at Chicago, county of Cook, and State of Illinois, have 5 invented certain new and useful Improvements in Gas or Oil Motors for Bicycles, which are fully set forth in the following specification, reference being had to the accompanying drawings, forming a part thereof.

10 The purpose of this invention is to provide an improved motor in the shape of a gas or oil engine for association with and to assist in propelling a bicycle or other vehicle. One specific purpose kept in mind as a motive for 15 the invention is to provide a motor adapted to operate with the least possible intervening mechanism upon the driving-wheel of the vehicle and at the same time to prevent the excessive strain upon the parts which results 20 when the mechanical connections from the piston-rod of the motor to the wheel are exposed to the shock of the explosion and the resultant almost instantaneous movement of the piston. To avoid making such direct 25 connection heretofore, motors have been constructed whose prime shaft—that is, the shaft having immediate crank connection with the piston—has a high rotary speed, from which proper speed-reducing train extends to the 30 vehicle-wheel. The objections to such train are obvious, and the necessity of a high rate of motion for the engine and its prime shaft which is involved in that mode of construction is seriously objectionable; and my invention 35 as to this point consists in causing the action of the piston under the force of explosion to store up power by coiling a spring whose uncoiling at any speed and at any time drives the vehicle-wheel.

40 A second specific feature consists in utilizing the drive-chain extending from the usual pedal - crank - shaft sprocket - wheel to the sprocket-pinion on the driving-wheel as the means of operating the valves and so determining the frequency of the explosions.

45 A third feature consists in the employment of devices under the control of the rider—preferably at the handle-bar—for shifting the valve-operating connections into and out of 50 the path of the driving-chain to cause and intermit the explosions at will. It comprises also a special form of piston and stem and

slide-bearings therefor, which constitute air-connections from the forward to the rear side of the piston, by which the outstroke of the 55 piston compresses air which enters behind the piston with the next charge, and in connection with this feature it comprises features of construction by which the air drawn in by the retreat of the piston and afterward 60 expelled through the air-ducts mentioned serves to cool the piston and stem, and it comprises also devices by which the compressed air, when admitted behind the piston, sprays the oil into the explosion-chamber. 65

My invention comprises also a special form of clutch mechanism by which the reciprocating motion of the piston is transmitted through a spring to the driving-shaft and a spring device in connection therewith by 70 whose tension the degree of compression attained for explosion is controlled.

My invention consists also in details of construction, which are set out in the claims.

In the drawings, Figure 1 is a side elevation of a bicycle having my improved motor associated therewith. Fig. 2 is a detail sectional view, on an enlarged scale, at the plane of the line 2 2 on Fig. 1. Fig. 3 is a plan view looking in the direction of the arrow 3 80 on Fig. 1. Fig. 4 is a rear end elevation of the cylinder and its connections with the cap-plate removed. Fig. 5 is a section at the line 5 5 on Fig. 4. Fig. 6 is a section at the line 6 6 on Fig. 4. Fig. 7 is an axial section 85 through the driving-clutch. Fig. 8 is a section at the line 8 8 on Fig. 7. Fig. 9 is a detail view of a portion of the drive-chain, showing the valve-operating cams thereon. Figs. 10 and 11 are transverse sections of the same 90 at the lines 10 10 and 11 11, respectively, on Fig. 1. Fig. 12 is an outer end elevation of the piston. Fig. 13 is an axial section through the same. Fig. 14 is an elevation of the forward or open-head of the cylinder. Figs. 15 95 and 16 are detail side and rear elevations, respectively, of certain links in the connections from the hand-lever to the valves and igniting-circuit switch. Fig. 17 is a detail side elevation of the drive-wheel and motor-frame 100 and mechanism thereabout, portions being broken away to disclose the valve-operating mechanism.

Fig. 1 shows a bicycle which has the cus-

tomary construction involving the so-called "diamond" frame A A' A² A³ A⁴, rear driving-wheel B, front steering-wheel B', steering-fork B¹⁰, handle-bars B¹¹, seat-post or 5 strut-post C for the diamond-frame saddle D, crank-shaft having pedals E E', driving sprocket-wheel E', drive-chain E², drive-pinion E³ on the driving-wheel, and the customary accessory details of said parts. The construction of all these parts requires no detail explanation, since so far as they depart from customary structures the departures are matters of design or unimportant detail, except in that the arms of the rear forks A' and 10 A² are spread at the rear axle more widely than ordinarily required, the additional space being necessary to admit the engine. The engine, comprising the cylinder F, with its piston having a tubular stem F², guided on 15 the tubular central guide F³, which is part of an air-duct of which the return branch F⁵ makes up a part of the engine-framework, is itself mounted in a supplemental tubular frame consisting of two triangular frames, 20 each composed of triangularly-arranged bars G, G', and G², said frames being located at opposite sides of the wheel and being united at their corresponding angles—to wit, at the rear angle by the bolt which connects both 25 frames to the rear cylinder-head, as herein-after more particularly described, at the forward angle by attachment to the rear-wheel axle, where said frame is secured by the same nut which secures the rear angle of the diamond frame to said axle, and at the top by 30 the tie-rod G⁴, by which also said angles of the two triangular frames, respectively, are connected by tubular rods G⁵ G⁵ to the apex of the bicycle-frame, junction being made 35 40 immediately in the rear of the seat-post by the bolt g⁵.

The engine-cylinder F has its rear head F⁴ provided with lateral lugs F⁴⁰ F⁴¹, extending at opposite sides horizontally and affording 45 means for attaching the right and left triangles of the engine-supporting frame above described, said triangles having threaded terminals g g, which pass through eyes in the lugs F⁴⁰ and F⁴¹ and receive nuts g' g' behind 50 said lugs. The cylinder F is supported at its forward end by means of a boss F² on the outer side of the forward head F^a, which affords a seat for a supplemental post G³ of the right-hand triangle of the supplemental frame and a yoke or clasp f', applied outside 55 said post G³ and bound fast to the lug F^{a2}.

The piston-stem guide F³ and the return branch F⁵ of the air-duct extend close along-side the strut-post C of the diamond frame 60 and are bound rigidly by clamps f³ f³, completing thus the support of the engine with respect to the engine-framework of the machine. This construction, it will be observed, permits the detachment from the bicycle of 65 the engine and its supporting-frame. Such detachment being effected by removing the bolt g⁵ at the rear of the seat-post and disen-

gaging the lower angle of the supplemental frame from the rear axle at both ends of the latter and removing the clamps f³ f³, the supplemental frame, tie-rod G⁵, and the entire engine may be removed, and the operating connections, hereinafter described, which extend from the vicinity of the handle-bar to the engine-valve mechanism, being also disconnected at any convenient point near the steering-head, may be removed with the engine. 70 75

I will now describe the construction and operation of the engine. 80

The cylinder F, I prefer to make of light metal having a high conductivity of heat, as brass, so that it may cool rapidly by the movement of the vehicle through the air and without the necessity for a water-jacket. 85 The rear head of the cylinder is formed by means of a collar F⁴, screwed onto the tubular body F and having, besides the lugs F⁴⁰ F⁴¹, above mentioned, for attachment to the frame, a further extension F⁴² at the 90 lower side which contains the valve-seats and exhaust and inlet connections. This collar is closed at the rear by a cap-plate F⁴⁵, which is bound in place by a yoke F⁴⁶, said yoke being pivoted at its lower end on a stud-bolt f⁴⁷, which is rooted in the lower side of the extension F⁴² and constitutes a pivot on which the yoke may swing in a plane transverse to the cylinder, the opposite end of said yoke having a hook-nose f⁴⁶, which when the 100 yoke is swung across the head or cap-plate F⁴⁵ engages the flange f⁴ on the collar F⁴, so that a clamping-bolt F⁴⁷, which is screwed through the center of the yoke F⁴⁶ and bears against a central boss f⁴⁵ on the cap-plate, 105 serves to clamp the cap-plate firmly onto the end of the collar F⁴, thus completing the head of the cylinder. 110

The particular construction described, it will be observed, renders the attachment of the yoke to the structure permanent, so that it is in no danger of being lost by accident, even when it is swung down for the purpose of moving the head. For the same reason the head may be pivoted on the same bolt and moved out of position by merely swinging on the bolt downward. 115

F' is the piston-head. It is provided with a forward face F¹⁰, which completely closes the cylinder, and back of said face it is chambered, 120 as seen in Figs. 12 and 13, a central cavity F¹¹ having communication by way of the port f¹¹, which is controlled by the valve F¹², with the annular cavity F¹³, said annular cavity being interrupted in part by metal left standing to receive bolts F¹⁴ F¹⁴, by which a rear plate F¹⁵ is secured to the piston-head, said rear plate having a centrally-threaded boss f¹⁵, which opens into the central chamber F¹¹ and serves to receive the tubular stem F² of 130 the piston, which is screwed into said boss, thus making said stem a continuation of said central chamber F¹¹, into which the valve F¹² opens, so that air entering through the an-

nular chamber F^{13} and passing the valve F^{12} reaches said central stem F^2 .

The stem F^2 is guided in the forward head F^a , which is screwed onto the forward end of the cylinder F , and has a centrally open hub $F^{a'}$, in which the tubular stem F^2 obtains seat and guidance, said central hub being connected by radial arms to the outer threaded flange of said head. The tubular stem F^2 telescopes with the tubular guide F^3 , the latter passing within the former, said guide being open at its end, thus telescoped within the tubular stem and the latter having a suitable stuffing-box at its end to insure air-tight seating about the guide.

For greater security in this respect and to give stiffness desirable for the connection with the driving-clutch, hereinafter described, I fortify the tubular stem for a distance back from the end by an outer sleeve F^{21} , which is fitted closely outside said stem and provided with a threaded connection thereto at f^{21} and extends somewhat beyond it and receives the stuffing-box cap F^{22} , suitable packing f^{22} being interposed between the guide F^3 and the end of the sleeve F^{21} , which extends beyond the end of the stem and said stuffing-box cap. The guide F^3 has the return branch F^5 , which leads into the chamber f^{40} , in the lower extended portion of the rear head of the cylinder, which chamber communicates by way of a port controlled by the inlet-valve H with the explosion-chamber f^{42} . A check-valve is located at any suitable point in the duct to retain any desired proportion of the air compressed by the outward travel of the piston. I have represented such check-valve as located at F^6 at the end of the guide F^3 , so that the air compressed in the duct beyond that point—that is to say, in the return branch F^5 and in the chamber f^{40} —is retained, while so much as is contained in the guide F^3 up to the check-valve acts as a recoil-spring to assist in returning the piston after its outward stroke caused by the explosion.

In the forward wall of the extension F^{42} of the rear head of the cylinder which projects below the cylinder proper are located two chambers f^{40} and f^{41} , the first communicating by way of the port controlled by the air-inlet valve H , as above stated, with the explosion-chamber and the second communicating by way of the exhaust-valve H' with the same chamber. The stems h and h' of these valves respectively extend through the chambers f^{40} and f^{41} , respectively, and through stuffing-boxes f^a f^b outside said chambers, respectively, and obtain further guidance in a lug F^{60} , formed on a fortifying-strap F^6 , which encircles the cylinder F , said lug depending below the cylinder in proper position to support and guide the valve-stems. Forward of said lugs the stems are joined, the continuations of said stems h^a and h^b , respectively, being adapted to oscillate in vertical planes about the joint, and both said stems are deflected inwardly—that is, toward the plane

of the drive-wheel—and extended forwardly parallel to each other at their forward terminals, being lodged at the forward ends 70 in vertical slots f^{a2} and f^{a3} in a depending web formed on the forward head F^a of the cylinder. (See Fig. 14.) At their forward ends these valve-stems are connected, respectively, by links h^c and h^d to the link h^e , Fig. 75 15, which is connected to the rearwardly-extended arm of a bell-crank lever H^b , mounted at H^b near the upper end of the right-hand post G^2 , the upstanding arm of said bell-crank lever being connected by a link H^c forward to the upstanding arm of a bell-crank lever H^b , suitably fulcrumed at H^a near the forward end of the upper bar A of the veloci-pede-frame, the forwardly-extending arm of said bell-crank lever being forked to engage 85 a collar H^d , which slides on the steering-head and is connected by a link H^e upwardly to a lever H^f , which is in position and in the form of a customary brake-lever, and in practice I utilize said lever for that purpose when it 90 is not required for the purpose of operating a brake, the latter being removed from the machine, as is a common custom with experienced riders.

It will be observed that the operation of 95 the lever H^f in a manner which usually sets the brake will lift the forward ends of the jointed valve-stems h^a and h^b , and the opposite movement of the lever will depress them. On the ends of the stems h^a and h^b , forward of the connection thereto of the links h^c and h^d , are contact-rolls h^{a1} and h^{a2} , which when the forward ends of the stems are elevated are in the paths, respectively, of certain cams E^{20} E^{21} on selected links of the drive-chain 100 E^2 , the path of the cams E^{20} being such as to bring them into collision with the roller on the end of the stem h^a , while the cams E^{21} are in position at the inner side of the chain to bring them into collision with the roller on the end of the stem h^b . When, however, the mechanism connected with the lever H^f is operated by the rider releasing the end of said lever, as for releasing the brake, the ends of 110 said stems h^a and h^b are depressed out of the track of the cams with the result of discontinuing the action of the engine.

When gasoline or other hydrocarbon oil is used to generate the gas for explosion, the supply of such oil is carried in a receiver L , 120 which is supported within the triangular frame G G' G^2 on the left-hand side of the wheel, and a suitable duct L' conducts the oil from the reservoir to an oil-chamber h^3 , formed in the depending extension of the rear head of the cylinder immediately below the body of the cylinder, said oil-chamber being connected by small ports, one of which is shown at h^{30} , leading to the seat of the inlet-valve H , said ports being closed at their entrance into the oil-chamber h^3 by a valve H^3 , 125 whose stem extends out through a suitable stuffing-box and is connected to the stem of the exhaust-valve H' , as by laterally-project-

ing lug h^{20} on the stem h' of said last-mentioned valve H' , so that both valves H' and H^3 may be operated simultaneously by one device, admitting a new charge of oil to the 5 ports h^{30} simultaneously with the opening of the exhaust-valve.

The explosion may be produced (and I have illustrated mechanism for producing it) by an electric spark passing between two electrodes within the explosion-chamber f^{42} .

I have shown only conventionally and without designing to make the illustration complete or specific insulated electrodes M M , Fig. 4, terminating within said chamber, 15 and an insulated secondary circuit, including said electrodes M , and leading by any convenient course along which a properly-insulated wire may be supported on the frame to the induction-coil M^2 , which, with the battery 20 M^3 , is contained within a receptacle M^4 , hung on the frame, the primary circuit extending from the pole M^{30} of the battery to the induction-coil, and thence to the insulated spring-arm M^{20} , which carries the armature m^{20} , and 25 thence to the frame, the wire from the opposite pole M^{31} of the battery extending insulated to the insulated contact-piece M^5 on the switch-lever M^6 , said contact-piece M^5 being in the path of the cam E^{20} when the roll H^{31} 30 is in said path, so that after the inlet-valve has been opened and closed again, whereby an explosive charge has been admitted to the explosion-chamber, a spark or series of sparks is caused to pass between the electrodes M M 35 to ignite said charge.

The lever M^6 is pivotally attached to the link H^c and is lodged on the stiff finger W , projecting from the frame, so that when the link is depressed the forward end of the 40 switch-lever rises and the contact-piece is carried out of the path of the cam during the same time that the roll H^{31} is out of the path, and the igniting-sparks are therefore intermittent when the operation of the valve is 45 intermittent.

The operation of the engine proper, independently of its driving connection to the wheel, may be understood as follows: The rider having mounted the machine and 50 started by means of the pedals in the usual manner, desiring to utilize the power of the engine, operates the lever H^c , depressing it away from the handle, with the result that the ends of the levers h^a and h^b are brought into 55 the path of the cams E^{20} E^{21} on the drive-chain. When the cam E^{21} collides with the lever h^b , the valve H^3 is opened and oil is fed from the oil-chamber h^3 into the duct h^{30} , which leads to the face of the valve H , and when 60 afterward the cam E^{20} collides with the lever h^a some portion of the oil will flow into the explosion-chamber f^{42} , and eventually sufficient vapor will exist in the chamber to cause an explosion when the cam E^{20} operates the 65 switch to close the circuit and causes a spark in the chamber. To hasten this result, the operator may before mounting operate the

piston by hand, reciprocating it once or twice, whereby air will be compressed in the duct F^5 behind the valve H , so that as soon as said valve is opened, after oil has been admitted, the oil will be sprayed into the explosion-chamber and be ready for explosion immediately. The piston, being driven outward by the explosion and compressing the air in 75 the guide F^8 and in the duct F^6 , will remain at the forward end of the cylinder until the cam E^{21} , colliding with the stem h^b , opens the exhaust-valve, permitting the compressed gases behind the piston to escape, whereupon 80 the air compressed in the guide F^8 up to the check-valve F^6 will react and send the piston back, and the check-valve being closed, the cam E^{21} having passed off the end of the stem h^b , the piston is ready for another outward 85 movement when the next explosion is produced, as already described.

The opening movement of the exhaust-valve unseats the valve H^3 , as above described, and admits a new charge of oil to the port h^{30} , 90 which is ready to be taken in with the next charge of compressed air when the valve H is opened.

I will now describe the mechanism by which the engine is connected to and made to actuate the drive-wheel, said mechanism having also a function in respect to the action of the engine itself in that it contains the means for retracting the piston forcibly, so as to compress the air behind it in the explosion-chamber to a tension favorable for the best results in the development of power upon such explosion. The connection between the piston and the driving mechanism of the velocipede consists of a clutch mounted on the drive-wheel axle and having a flexible strap connection with the piston-stem, whereby the outward travel of the piston rotates the clutch to coil a spring which is connected to the driving-wheel and which in reacting rotates 100 the said wheel. P is the shell or outer cylinder of the clutch. Q is the strap which connects said clutch to the piston-stem, the strap being passed around the periphery of the cylinder P , one end being attached to it at q , the 105 other end being attached to the collar F^7 , clamped on the piston-stem.

The cylinder or shell P has annular heads P' and P^2 , which at their inner circumferences, respectively, are seated with ball-bearings on the collars P^3 and P^4 , respectively, the collar P^3 being rigid with the extension B^{10} of the hub B' of the drive-wheel B , said extension being screwed through the end of the hub proper, as seen in Fig. 7, and made 115 secure against rotation in any suitable manner, as by a pin or cam b^{10} .

The collar P^4 is rigid with the axle b of the wheel B , and at the opposite side from the bearing of the head P^2 thereon it has ball-bearings at P^{41} for the outer end of the extension B^{10} .

Within the outer cylinder P of the clutch is the inner cylinder P^5 , which has one annu-

lar head P^5 at the inner side, which is seated at its inner circumference, with ball-bearings (shown at p^5) on the collar P^3 . The cylinder P^5 is peripherally ratcheted, ratchet-teeth being shown at p^5 , and a dog R , pivoted within the outer cylinder P , engages the ratchet-teeth p^5 , said teeth being faced and the dog being extended in proper direction to cause the outer cylinder to drive the inner when the strap Q is drawn off the cylinder when the piston makes its outward movement under the effect of an explosion.

To the inner cylinder is pivoted a dog R' , which engages the ratchet-rim P^{42} on the fixed collar of the disk P^4 , the teeth of said ratchet-rim being faced and the dog being extended in a direction to permit the dog to ride back over the ratchet when the inner cylinder P^5 is rotated by the outer cylinder in the manner described. A coil-spring S has its inner end attached at s to the hub extension B^{10} and its outer end attached at s' to the inner surface of the inner cylinder P^5 , said spring being coiled in such direction that it is wound up or tightened by the rotation which the inner cylinder receives from the outer when the strap is drawn off from the latter.

From this construction it will result that when the spring is coiled up in the manner described the dog R' , engaging the ratchet-rim P^{42} on the collar P^4 , which is fixed with respect to the axle, retains the spring thus coiled, which can react by uncoiling from the inner end, and thereby rotating the extension-hub B^{10} , to which said rim is attached, and thereby rotating the drive-wheel.

On the outer side of the outer head P^2 of the outer cylinder P the nut P^6 , which is screwed onto the axle b , holds the inner end of a coiled spring T , whose outer end is engaged with a stud p^2 , which is rooted in and projects from the outer face of the head P^2 of the outer cylinder. This spring is coiled in the same direction as the spring S and is coiled and put under tension by the same movement which coils the inner spring. Being, however, connected directly at its outer end to the outer cylinder and tending to uncoil when relieved from the coiling movement of the outer cylinder it tends to reverse the movement of the outer cylinder, retracting the pawl R over the ratchet p^5 to its original position, and thereby winding up again the strap Q and retracting the piston. The tension of this spring T may be adjusted as desired by rotating the nut P^6 on the axle b , and it may be so adjusted as to retract the piston with any desired force less than that produced by the explosion which drove the piston outward, and thereby compress the air behind the piston into the explosion-chamber to such tension as it is deemed desirable. The outer spring T may be inclosed by a cap T' , which may be screwed onto the outer end of the axle b , as seen in Fig. 7. The hub extension B^{10} having ball-bearings at its outer ends at P^{41} , the necessity for ball-bearings elsewhere at

that end of the hub is removed, the usual ball-bearings being, however, provided at the opposite end of the hub on the other side of the wheel. These opposite ball-bearings are not illustrated, being of the ordinary construction, the ball-case being shown at B^{12} in Fig. 2.

I claim—

1. In combination with a velocipede, a gas or oil motor operatively connected with the driving-wheel of the velocipede; the velocipede drive-chain having cams which in the travel of the chain collide with operating connections of the motor-valves, and thereby actuate the valves.

2. In combination with a velocipede, a gas or oil motor mounted on the velocipede-frame; electric igniting devices pertaining to said motor; the circuit which energizes the same; a switch in said circuit whereat it is adapted to be opened or closed, and a cam on the velocipede driving-chain adapted to operate said switch to open and close the circuit, and thereby to cause ignition in the explosion-chamber to the motor.

3. In combination with a velocipede, a gas or oil motor and devices which actuate the controlling-valves thereof, connections adapted to be operated by the rider at the vicinity of the handle-bar for dislocating the valve-actuating devices to prevent at will the action of said valves.

4. In combination with a velocipede, a rotatable clutch on the driving-shaft thereof, adapted to be reciprocatingly rotated exteriorly and to communicate rotation to the shaft continuously in one direction, a spring through which such rotary motion is communicated from the clutch to the shaft and a gas or oil motor mounted on the velocipede-frame and having its piston connected to the exterior member of the rotatable clutch to reciprocatingly rotate the latter as the piston reciprocates.

5. In combination with a velocipede, a clutch mounted on the driving-shaft thereof having its exterior member adapted to be reciprocatingly rotated and to communicate rotation continuously in one direction to the shaft; a spring through which such rotation is communicated to the shaft, a gas or oil motor mounted on the velocipede-frame and having its piston operatively connected to said outer member of the clutch to reciprocatingly rotate said member as the piston reciprocates; and a spring which is put under tension by the rotation of the clutch in the driving direction when the piston is traveling outward and which reacts to reverse the rotation of said clutch member, whereby such spring operates to retract the piston.

6. In combination with the cylinder of the motor, the piston having a tubular stem, a tubular guideway adapted to be fixed with respect to the cylinder and adapted to be telescoped with the tubular stem of the piston as the latter reciprocates; a duct of which

said tubular guideway forms a part; an explosion-chamber back of the piston to which such duct leads; a valve adapted to be mechanically operated to control communication of the duct with the explosion-chamber, and a check-valve in the duct antecedent to the first-mentioned valve adapted to hold the air which is forced past it by the outward travel of the piston under tension between 5 said valves; and suitable means for operating the first-mentioned valve to admit the compressed air to the explosion-chamber.

7. In combination with a chain-driven velocipede, a gas or oil motor mounted thereon having a combustion-chamber and electric igniting devices associated therewith; a circuit which energizes the same containing a switch at which the circuit is normally open and which is adapted to be operated to close the 15 circuit; the controlling-valves of said motor having mechanical operating connections; cams on the driving-chain of the velocipede adapted to collide with said connections to operate said valves and adapted also to collide with said switch to operate the same to 20 cause ignition.

8. In combination with a chain-driven velocipede, a gas or oil motor mounted thereon having a combustion-chamber and sparking 25 electrodes therein, an electric induction-coil and a battery which energizes the same having its secondary circuit extending to said electrodes, the primary circuit including the frame and an insulated contact-piece; a cam 30 on the driving-chain of the velocipede adapted to collide with said contact-piece as the velocipede is driven.

9. In combination with a chain-driven velocipede and a gas or oil motor mounted thereon 35 on the cylinder of the motor having an explosion-chamber communicating therewith behind the piston; the compressed-air duct in which the air is compressed by the outward travel of the piston; a valve which controls 40 the communication of said duct with the explosion-chamber; an exhaust-port and a valve which controls the same, the stems of said 45 valves being extended outside the cylinder and terminating in the vicinity of the path of the drive-chain of the velocipede; and cams on said drive-chain adapted to collide with 50 said stems respectively.

10. In combination with a chain-driven velocipede, a gas or oil motor mounted thereon 55 having the stems of its inlet and exhaust valves extended outside the cylinder and terminating in the vicinity of the drive-chain; cams on said chain adapted to collide with said stems to operate the valves, said stems 60 being jointed and adapted to be flexed at such joints to carry their terminals out of the path of the cams; a finger-lever at the handle-bar, and mechanical connections therefrom to the stem, whereby at will they may be flexed 65 at their joints respectively to carry their terminals out of the paths of said cams respectively.

11. In combination with a chain-driven velocipede, a gas and oil motor mounted thereon having the stems of the inlet and exhaust 70 valves extended outside the cylinder and provided with flexible joints and having terminals which are adapted to stand in the vicinity of the drive-chain; the electric igniting devices and the circuit in which they are energized containing an insulated contact-piece 75 at which the circuit may be closed to cause ignition; the drive-chain and cams thereon adapted as the chain travels to collide with the terminals of the valve-stem and with the contact-piece to operate said valves and close the circuit; a movable arm on which said contact-piece is mounted adapted to be moved to carry the contact-piece out of the path of the cam, and mechanical connections from 80 said valve-stems and from said movable arm extending to the vicinity of the handle and there adapted to be operated at will, whereby the operator may at will dislocate the valve-stem terminals and contact-piece to interrupt 85 the operation of the motor.

12. In combination with the cylinder, the piston having a tubular stem and a central chamber with which said piston communicates, and an annular chamber forwardly 95 open encompassing said central chamber and a valve which controls communication between said chambers adapted to open from the annular into the central chamber, and a fixed tubular guide about which the tubular 100 stem of the piston telescopes as the piston reciprocates, and a check-valve which prevents air from entering, and permits it to escape from said tubular guide, whereby the retreat of the piston causes it to draw in exterior air 105 through the annular chamber and pass the same into the central chamber and tubular stem, and the return of such air when the piston advances is prevented.

13. In combination with a cylinder, the piston having a forwardly-open chamber and a second chamber communicating therewith; a tubular stem communicating with said second chamber, and the valve controlling communication between said chambers adapted 110 to open into the stem-connected chamber; a tubular guide with which said tubular stem telescopes; a duct of which said tubular guide constitutes a part, and a check-valve in said 115 tubular duct whereby the retreat of the piston draws in atmospheric air through the forwardly-open chamber, and its advance compresses such air beyond the check-valve.

14. In combination with a cylinder, the piston having a forwardly-open chamber and a 120 second chamber communicating therewith; a tubular stem communicating with said second chamber, and the valve controlling communication between said chambers adapted 125 to open into the stem-connected chamber; a tubular guide with which said tubular stem telescopes a duct of which said tubular guide constitutes a part, and a check-valve in said 130 duct at a point somewhat remote from the in-

let end thereof adapted to seat toward the piston, whereby outward travel of the piston compresses air in said duct, and the portion thereof which is not forced past the check-
5 valve operates elastically to start the piston back.

15. In combination with an explosive-motor and a shaft which it is designed to rotate, a clutch on such shaft having its exterior member adapted to be reciprocatingly rotated, and an interior member which is actuated in one direction by the outer member; suitable means for locking said interior member against rotation in the other direction; and
15 a spring connecting said interior member with the shaft and adapted to be put under tension by the rotation of said interior member, whereby the recoil or reaction of such spring rotates the shaft in the direction in
20 which the inner member of the clutch is rotated by the outer member, but independently of the time of such rotation.

16. In a velocipede, in combination with

pedal-operated driving mechanism, an explosive-motor mounted on the velocipede-frame 25 and operatively connected to a driving-shaft of the velocipede; cams on a moving part of said pedal-operated driving-train, the controlling-valves of such motor having their stems provided with terminals adapted to 30 stand in the path of such cams and to be moved out of such paths; mechanical connections extending to the vicinity of the handle-bar and adapted to be operated at will to move said terminals into and out of the path 35 of the cams, whereby pedal-operated mechanism of the velocipede may at the will of the rider be caused to control the motor.

In testimony whereof I have hereunto set my hand, in the presence of two witnesses, 40 at Chicago, Illinois, this 15th day of March, 1897.

WENSEL MORAVA.
